(57) **CLAIM**

I claim the ornamental design for a connector for canopy system, as shown and described.

DESCRIPTION

FIG. 1 is a perspective view of a connector for canopy system;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing of rod is for the purpose of illustrating the connector for canopy system and forms no part of the claimed design.
